UNITED STATES PATENT OFFICE.

JOHN P. SCHAEFER, OF LOUISVILLE, KENTUCKY.

PROCESS FOR REMOVING PAINT.

1,357,730.

Specification of Letters Patent.

Patented Nov. 2, 1920.

Application filed June 26, 1920. Serial No. 392,065.

To all whom it may concern:

Be it known that I, JOHN P. SCHAEFER, a citizen of the United States of America, residing at Louisville, in the county of Jefferson and State of Kentucky, have invented certain new and useful Improvements in Processes for Removing Paint, of which the following is a specification.

This invention relates to processes and 10 apparatus for removing paint from painted surfaces such as the bodies of automobiles and the like.

It has been customary to remove paint from various painted surfaces with a solution of sodium-hydroxid in water, a sponge and rubber gloves being employed to enable the operator to properly apply the solution. This process is, in many instances, inconvenient and consumes a great deal of time.

20 The principal object of the present invention is to provide an improved process of this character, and the necessary mechanism to carry the process into execution.

With the above, and other objects in view 25 as will be hereinafter apparent, the invention consists in general of an improved process for removing paint from painted surfaces, together with certain novel details of construction and arrangements of parts in 30 an apparatus suitable for carrying the process into operation, said process and apparatus being hereinafter fully described, illustrated in the accompanying drawings and specifically claimed.

35 In the accompanying drawings, like characters of reference indicate like parts in the several views, and:

Figure 1 is a side elevation of an apparatus suitable for carrying the process into 40 operation.

Fig. 2 is a section on the line II—II of Fig. 1.

In the apparatus herein disclosed, there 45 is provided an elongated cylindrical tank 10 similar to the ordinary kitchen water heating boiler, but disposed with its axis horizontal. This tank is supported at an elevation on a suitable frame or stand 11, and is provided at the center of its upper side 50 with a filling pipe 12 terminating at its upper end in a funnel 13, a valve 14 being provided to close the funnel from the pipe. A branch pipe 15 leads from the pipe 12 and is provided with a valved connection 16 55 having its end threaded as at 17 so that the

washing hose (not shown) may be connected thereto. Extending centrally into one end of the tank is a water supply pipe 18 provided with a shut-off valve 19. The portion of this pipe which extends into the tank 10 is bent downward as at 19 and terminates near the bottom of the tank.

At 20 is an ordinary water heater supplied with gas through the valved pipe 21 and from this heater lead the circulating 65 pipes 22 and 23.

In operation the valve 19' is opened as is also the valve 14. The tank 10 then fills with water whereupon the valve 19' is closed. The valve 14 being open about thirty pounds 70 of sodium hydroxid are introduced through the funnel 13 and pipe 12 to the tank 10. The heater 20 is then started in operation and the water will circulate in the direction of the arrows on the pipes 22 and 23 until 75 the entire tank is thoroughly heated. The washing hose having been connected at 17 the valves 16 and 19' are opened the valve 14 being at this time closed. The result of this is that clear fresh water is forced 80 downward from the pipe end 19 thus stirring up the solution in the tank 10 and, since the tank is full, forcing a portion thereof up through the pipe 15 and the hose. This hose is then used to apply the solution to 85 the painted surface. Now owing to the peculiar arrangement of the pipe 19 there is a continuous agitation of the water in the tank and a thorough stirring and mixing results. Consequently the solution flowing 90 from the pipe 15 and used on the painted surface gradually weakens until finally all of the solution has been forced out of the tank and only clear water flows from the pipe 15 so that the surface, from which the 95 paint has now been removed, is washed down with clear water.

This method of utilizing the property of sodium-hydroxid to remove paint is found by practice to be highly economical since 100 the hard coat on the outside of the painted surface is attacked by the stronger solution while, as the paint softens under the action of the chemical, a weaker solution is used and thus economy results in the quantity of 105 chemical necessary. Moreover this method is found by experience to greatly increase the rapidity of the operation over the method of applying the solution by hand.

There has thus been provided a simple 110

and efficient process and apparatus for carrying the same into execution of the kind described and for the purpose specified.

Having thus described the invention, 5 what is claimed as new, is:—

1. The process of removing paint from painted surfaces which consists in preparing a bath of strong sodium-hydroxid solution and thereafter gradually weakening 10 and agitating the same, the solution being applied continuously to the painted surface from its strong to its weakened state.

2. The process of removing paint from painted surfaces which consists in preparing 15 a bath of strong sodium-hydroxid solution in water and applying the same to the painted surface and simultaneously and continuously injecting fresh water into said bath in such manner as to mix and weaken

the bath during the entire period of application whereby a gradually weakened solution is applied to said painted surface.

3. The process of removing paint from painted surfaces which consists in preparing a bath of strong sodium-hydroxid solution 25 in water and applying the same to the painted surface and simultaneously and continuously injecting fresh water into said bath in such manner as to mix and weaken the bath during the entire period of application whereby a gradually weakened solution is applied to said painted surface, said 30 fresh water being injected until the bath contains only clear water and the application being continued with said clear water.

In testimony whereof I affix my signature.

JOHN P. SCHAEFER.
